CLAIM

The ornamental design of a frame for a pressure washer, as shown and described.

DESCRIPTION

FIG. 1 is a front perspective of the frame for a pressure washer;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof;

FIG. 8 is a front perspective view of a frame for a pressure washer according to another embodiment;

FIG. 9 is a front elevation view of the embodiment of FIG. 8;

FIG. 10 is a rear elevation view of the embodiment of FIG. 8;

FIG. 11 is a right elevation view of the embodiment of FIG. 8;

FIG. 12 is a left elevation view of the embodiment of FIG. 8;

FIG. 13 is a top plan view of the embodiment of FIG. 8; and,

FIG. 14 is a bottom plan view of the embodiment of FIG. 8. The broken lines showing portions of a frame for a pressure washer are included for the purpose of illustrating environment and form no part of the claimed design.
